UNITED STATES PATENT OFFICE.

JOSEPH SZAKÁCS, OF SANDWICH, ILLINOIS.

ICE-CREEPER.

1,175,485.

Specification of Letters Patent.

Patented Mar. 14, 1916.

Application filed October 20, 1915. Serial No. 56,869.

To all whom it may concern:

Be it known that I, JOSEPH SZAKÁCS, a subject of the King of Hungary, residing at Sandwich, in the county of Dekalb and ⁵ State of Illinois, have invented new and useful Improvements in Ice-Creepers, of which the following is a specification.

This invention relates to improvements in non-slipping devices as applied to the heels ¹⁰ of boots and shoes under the common term of ice-creepers.

One of the objects of the invention is to provide means which are readily applied to, or removed from, the heels of ordinary foot ¹⁵ coverings, that effectually engage with a surface trodden upon, preventing slipping or sliding thereon, irrespective of the condition of the surface, as frozen, icy, greasy or otherwise.

²⁰ A second object is to provide with such appliances, means whereby a resilient or springing effect is obtained, materially reducing the shock or jar of walking, rendering the same particularly agreeable and ²⁵ pleasant.

These objects are attained by the novel construction and arrangement of parts hereafter described and shown in the accompanying drawing, forming part of this specification and in which:

³⁰ Figure 1 is a plan view of the structure, made in accordance with the invention. Fig. 2 is a sectional view of the same, taken on line 2—2 of Fig. 1. Fig. 3 is a plan view ³⁵ showing a modified form of creeper. Fig. 4 is a sectional view taken on line 4—4 of Fig. 2, and Fig. 5 is a side elevation of the creeper, indicating its application to a shoe-heel.

⁴⁰ The appliance consists of a plate 10, shaped to agree in its outline, with a shoe heel and is provided at the front with a pair of widely disposed, upstanding lugs 11, having rearwardly turned spurs 12 adapted to ⁴⁵ engage in the material of the shoe heel, so as to be retained firmly in position. The sides of the plate have upturned lugs 14 adapted to make contact with the sides of the shoe heel so as to prevent lateral action ⁵⁰ when engaged thereon.

At the curved rear portion of the plate ¹⁰ is another lug 15, having a reinforcement ¹⁰ 16, secured to the under side of the plate 10 by the rivet 17 in such manner that the reinforcement and lug are united substantially integral, presenting a thickness suitable to

receive the threads of the winged clamp screw 18, provided with a spur point 19, extending toward the corresponding spurs 12, at the front of the heel, so that as the screw ⁶⁰ is turned inwardly the point enters the back of the heel firmly securing the plate upon it.

The foregoing description applies equally to both forms as shown in Figs. 1, 2 and 3, 4.

In Fig. 1, the plate is formed with downwardly depending lugs or projections 22 and 23, the same being substantially wedge shaped, with sharp points, adapted to engage with the surface trodden upon under weight of the person wearing them; as will ⁷⁰ be noticed, these projections are spaced so as to distribute the weight uniformly. At the front of the plate 10 is secured a spring element 25, by the rivet 26, to the lower side, the end of the member being broadened and ⁷⁵ turned upwardly, tightly engaging with the front edge of the plate 10 thereby assisting in holding it firmly in position; this spring element extends rearwardly to about the back of the heel and is formed with two lateral members 28, the edges of which are sharply serrated as at 29, and turned down so as to stand parallel, leaving a space between the heel plate and upper portion of the spring element under normal conditions. ⁸⁵ When a person's weight is placed on the plate, the spring member 25 is forced up against the plate, while at the same time the spurs or serrations are forced into the surface. Thus the step is cushioned and the ⁹⁰ foot assisted in rising by the action of the spring as the weight is transferred from one to the other.

In Figs. 3 and 4 an adaptation is shown in which lugs 30 and 31 are formed integral ⁹⁵ with the plate, the front ends of the lugs 30 being curved as at 32, while the corresponding rear ends 33 of the back lugs are similarly bent inward, the bottoms of each of these lugs being serrated as at 34 and 35. ¹⁰⁰ The spring element 36 has an upturned edge 37 at the front and is held by the rivet 38 to the plate 10, its rear spring portions 40 being provided with serrations 41 and out-turned at their ends 42 whereby a better grip may be obtained upon the surface traveled over.

While I have shown and described preferred embodiments of my invention, I do not wish to be confined strictly thereto, as ¹¹⁰ I may modify the construction within the scope of the claims hereto appended.

I claim.

1. In a device of the class described, the combination with a plate and means for removably attaching the plate to a heel, of 5 spurs formed integrally with said plate, said spurs depending downwardly and adapted for engagement, a resilient member rigidly attached to the lower side of said plate near the front thereof, and normally spaced 10 therefrom at the rear, and a plurality of serrations formed on downwardly extending portions of said member.
2. In a device of the class described, the combination with a plate and means for removably engagement therefor, of serrated 15 lugs depending from said plate at the sides thereof, a spring element rigidly secured longitudinally below said plate at the front end thereof, parallel disposed downwardly turned 20 members having serrated edges formed with

said spring element and normally extended beyond the plane of said lugs and a plurality of serrations formed on said extending edges.

3. In a device of the class described, a 25 plate formed with reentrant spurs at the front, projections at the side and a lug at the rear, a reinforcement for said lug, a clamp screw in said lug and reinforcement, depending spurs on the bottom of said plate, 30 a spring secured at one end to the front of said plate, the other end being free and normally extended outward beyond said spurs, the edges of said spring being downturned, and teeth formed upon the edges of said 35 spring.

In testimony whereof I have signed my name to this specification.

JOSEPH SZAKÁCS.
